UNITED STATES PATENT OFFICE.

OLIVER J. WARREN, OF CHICAGO, ILLINOIS.

BOOT-CRIMP.

Specification forming part of Letters Patent No. 41,952, dated March 15, 1864.

To all whom it may concern:

Be it known that I, OLIVER J. WARREN, of Chicago, Cook county, Illinois, have Invented a new and useful Boot-Crimp; and I do hereby declare the following to be a full, clear, and exact description thereof, reference being had to the accompanying drawings, making part of this specification.

My invention relates to an improved form for the vise or clamp commonly employed by shoe-makers to stretch the upper-leather or fronts of boots over the "form" or block in the operation of crimping.

Figure 1 is a perspective view of my improvement in position on the form. Fig. 2 is a longitudinal section through the same.

A is a U-shaped piece, which I style the "crotch," whose outer sides, near their extremities, are scored or roughened to afford a secure grip. These roughened extremities I call the "inner" jaws, a a'.

Hinged in the manner represented to the two inner jaws, a a', are two outer jaws, B B', correspondingly roughened on their gripping-surfaces.

The outer jaws, B B', terminate in shanks b b', for a purpose that will be presently explained.

C is a screw having a head, D, capable of rotating about the point of said screw as on a pivot. The screw C occupies an aperture, a'', in the crotch A, in which it freely slides. The screw C also carries a wedge-formed nut, E, swiveled within a yoke, E', whose pressure against the jaw-shanks b b', incident to working of the screw, acts to force said shanks asunder, and to cause the jaws B B' to press toward the jaws a a' and to grip whatever is placed between them.

Operation: The front or upper-leather of

a boot such as represented at F, having been partially crimped in the brake, is placed over a form, G, and the screw C having been retracted, the crotch A is caused to straddle the form. The edges of the leather being now introduced between the jaws a and B on one side and the jaws a' and B' on the other side, the screw C is rotated until the wedge-formed yoke E' begins to press outward the shanks b b' of the outer jaws, B B', and the head D to press upward against the edge of the form. The yoke E', having thus been made to spread the shanks b b' to their extreme limit, becomes in turn a stationary abutment for the screw to advance through, and, by pressing the head D against the edge of the form, acts to draw the vise bodily away from the form, and consequently to stretch the leather.

An obvious advantage of the above over the common form of crimper is the facility afforded by the crotch for gripping the edge of the leather when distant from the edge of the form.

Having thus described my invention, the following is what I claim as new therein and desire to secure by Letters Patent:

The wedge-formed yoke E', inclosing the nut E and operating to spread the arms b b', in the described combination with the crotch A a a', outer hinged jaws, B b B' b', and screw C, arranged and operating substantially as and for the purposes specified.

In testimony of which invention I hereunto set my hand.

OLIVER J. WARREN.
